1

This invention relates to metal working machines and more particularly to machines for impressing configurations in sheet metal.

The invention embraces the provision of mechanism for impressing grooves into cylindrical tubing or pipe fabricated of sheet metal.

The invention comprehends the provision of mechanism, substantially automatic in its operation, for simultaneously impressing or rolling a plurality of grooves or depressions in the walls 10 of tubular members.

An object of the invention resides in the provision of automatic means for positioning a tubular member upon which work is to be performed in the machine, and of means brought into operation after positioning of the tubular member for rolling a groove in the peripheral cylindrical wall thereof.

Another object is the provision of means automatically brought into operation after work has been performed upon a tubular member for discharging the latter from the machine, and for automatically resetting various elements in position to receive and perform work upon tubular members successively supplied to the machine.

Another object is the provision of a machine of this character embodying electrically initiated, hydraulically operated mechanisms for causing the successive functioning of various elements of the mechanism whereby work may be quickly and inexpensively performed upon work supplied to the machine.

Still another object is the provision of a machine adaptable for performing work upon metal articles wherein various mechanisms and components of the machine are rendered adjustable to adapt the machine to receive work of varying dimensions and sizes thus greatly enhancing the utility of the invention.

Further objects and advantages are within the scope of our invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 11 is a schematic view of the electrical circuits and control elements of the machine.

While we have illustrated the machine of our invention as particularly adapted for rolling or impressing circumferential depressions or grooves in a thin walled cylindrical member as, for example, a muffler shell, it is to be understood that the machine may be used for performing work on other items wherever it may be found to have utility. As illustrated, the machine is shown as

adapted to impress a circumferential groove in the wall of a muffler shell adjacent each end thereof to provide an abutment to position end heads afterwards inserted in the ends of the shell. The machine of our invention is inclusive

35 of means for preliminarily supporting the shell or other work, means for centering or positioning the shell in the machine, groove impressing means, work or shell discharging means and other adjuncts and mechanisms forming elements of the invention.

Referring to the drawings in detail, the apparatus is inclusive of a frame 10, which in the embodiment illustrated is of hollow configuration, having a machined bed surface 11. Disposed within the interior of the hollow frame housing 10 is a supporting structure 14 upon which is mounted a motor 15 adapted to be operated by electrical energy. The motor 15 is arranged to drive a fluid or hydraulic pump 16 of conventional design, which is connected to a reservoir 17 by means of a tube 18, the reservoir 17 containing oil or other suitable fluid for actuating various elements of the machine or apparatus, as hereinafter described. The motor, fluid

55 pump and reservoir components may be posi-

tioned exteriorly of the machine if such arrangement is desired without departing from the spirit of the invention.

The frame 10 is formed with a horizontal surface 21 arranged rearwardly and above the surface 11 and is adapted to support a pair of brackets 22 and 23 arranged in spaced relation and secured to the frame 11 by means of bolts 24. The brackets 22 and 23 are formed at their upper portions with bosses 27 bored to journally support a shaft or arbor 28. Mounted upon a portion of shaft 28 projecting outwardly of bracket 22 is an arm 29 which is secured to and adapted to rotate with the shaft 28 by means of a key 30. A clevis 31 is connected to the outer end of the arm 29 by means of a pin 32. Secured to an interior lower wall portion of the frame 10 is a bracket 35 to which is articulately connected a cylinder 36 by means of a pin 37. Slidably disposed within the cylinder 36 is a piston 38 carried upon the lower end of a rod 39 the upper extremity of the rod being threaded into an opening in the clevis 31, the rod being locked to the clevis by means of a nut 40. The upper end of cylinder 36 is provided with a head 41 through which extends the rod 39, a stuffing gland of conventional construction being mounted in the head 41 to prevent leakage of fluid along the rod 39.

The shaft 28 is adapted to support the grooving means for impressing grooves in the work W. The grooving means is inclusive of a pair of similarly shaped, spaced sectors or members 44 which are formed with enlarged hubs or bosses 46, the latter being bored to snugly fit but be slidable along the shaft 28. The interior of each hub portion 46 is provided with a recess adapted to accommodate a block or key 47, while the shaft 28 is formed with a land or flat surface 48 arranged to fit and coincide with the flat surfaces of the blocks 47. Each of the hubs 46 is provided with a pair of threaded openings adapted to receive screws 50 for direct engagement with the blocks 46 for fixedly securing the sectors in adjusted position on the shaft 28.

The arcuate surface of each of the sectors is adapted to receive and position an arcuately shaped tang 52 formed upon a removable die or member 53. The die 53 is provided with a plurality of radially arranged openings to accommodate screws 54 which are threaded into registering threaded openings in the sectors in order to retain the dies securely assembled to the sectors 44. Each die member 53 is integrally formed with an arcuate projection 55 configurated to impress or form a suitable depression or groove in the work in a manner to be hereinafter explained.

The surface 11 of the machine frame provides a support for a pair of spaced work supporting means 58 and 59. As each of the work supporting means are of identical construction, a detailed description of one of said means will suffice. Each work supporting means is inclusive of a base plate 60, the lower surface being formed with a longitudinally arranged recess adapted to receive a strip or key 61. The strip 61 depends from plate 60 and snugly fits into the throat portion 62 of a longitudinally extending recess 63 of T-shaped cross section formed in the frame structure 10. The base plate 60 is secured to the frame by means of T-shaped bolts 64 mating in the recess 63, the bolts receiving nuts 65 to secure the plate 60 in position upon the surface 11. By releasing the nuts 65, the base plate may be adjusted longitudinally of the machine frame to adapt the machine for work of varying lengths.

Each base plate 60 supports a member 66, the lower surface of member 66 and the upper surface of plate having transversely arranged registering slots to accommodate keys or strips 68 for maintaining the plate 60 and member 66 in proper relationship. The member 66 is formed with elongated transversely extending slots to receive bolts 67 for securing the member 66 to the plate 60, nuts 68' being threaded on bolts 67 to secure the parts together. By releasing the nuts 68', the member 66 may be adjusted transversely of plate 60 to secure proper alignment of both work supporting head structures 58 and 59. Each member 66 is formed with integral upwardly extending bosses or projections 70 and 71, which are bored to receive aligned pins or pintles 72. Mounted upon the pins 72 and arranged for limited oscillatory movement with respect to member 66 is a housing or bracket 73 which supports and encloses the mechanism for carrying the work. The head 73 is resiliently held in its normal position by means of expansive coil springs 74, the latter surrounding studs 75 threaded into openings in the member 66. The required stress may be placed upon the springs by adjusting the nuts 76 engageable with washers 77 arranged above the springs, lock nuts 78 being used to maintain the adjustment. The purpose of the resilient positioning means for the head is to provide a relief in the event that the grooving die inadvertently over-rides a seam in the work.

Referring especially to Figure 3, each head 73 is formed with a generally cylindrical portion within which is disposed a pair of spaced bearings or bushings 80 and 81, which support a cylindrical sleeve 82, the latter being slidable in bearings 80 and 81. Secured to one end of sleeve 82 is a circular plate 83 fastened by means of screws 84, the plate 83 having a threaded opening to receive a rod 85, the same being retained in position by a nut 86. Disposed at one end of head 73 is a cylindrical extension or member 87 held in place by screws 88. Secured to member 87 is a circular plate 89 held in place by screws 90, the plate supporting a fitting 91, the latter provided with a cylinder 92. Slidably disposed within the cylinder is a piston 93 which is connected to the end of rod 85. The fitting 91 is provided with a stuffing gland 94 of conventional design surrounding the piston rod 85 to prevent leakage of fluid from the cylinder 92. The cylinder is provided with connections or fittings 98 and 99 for the admission to and withdrawal of fluid from the cylinder 92 for actuating the piston 93.

Positioned within the sleeve 82 are anti-friction or ball bearings 100 and 101 spaced apart by means of a spacer or sleeve 102. Journaled in the bearings 100 and 101 is a shaft 103 having, at its forward end, an enlarged head 104. The shaft 103 is held in assembled relation with the bearings 100 and 101 by means of nuts 105 threaded on to a reduced tenon portion at the other end of the shaft. Mounted upon the shaft head 104 is a generally cylindrical member or mandrel 108 which directly engages and supports the work W during work performing operations. The mandrel 108 is secured to the head 104 by means of screws 109, and is formed with an annular depression or groove 110, which, in effect, becomes the female portion of a die for forming a groove or depression 111 in the work W.

In forming grooves adjacent the ends of a muffler shell or work W, it is imperative that each groove 111 be equidistant from the end

of the shell, and we have provided means for automatically positioning the shell with respect to the grooving dies 55, 110 for accomplishing this purpose. An abutment 114 in the form of an annulus is slidably mounted exteriorly of the mandrel 108, the abutment 114 being provided with a peripheral flange or projection 115 which extends into an annular recess formed in an abutment retaining member 117. The latter is secured to an annular member 118 by means of screws 119, the member 118 being secured to the housing 58 by means of screws 120. The recess in the retaining member 117 is of a dimension to permit limited longitudinal movement of the flange 115 and abutment 114 so that the abutment 114, in engaging the end wall or edge of the work, may move relative to the retaining ring 117.

The abutment or work positioning stop 114 is resiliently urged toward its outermost position by spring means. An annular member 123 slidably supported upon the shaft head 104, and another member 124 threadedly mounted on head 104, are formed with a plurality of aligned openings in which are disposed expansive coil springs 126. The position of member 124 may be adjusted by manipulation of the same and locking member or nut 127 also mounted upon a threaded exterior portion of the shaft head 104. We have found that it is desirable, in order to satisfactorily equalize the work between the supporting heads, that the springs 126 be of varying expansive force. In practice we have found that the use of nine springs, in sets of three, each set of slightly different expansive pressure enhances the equalization in positioning the work, although any number of springs of equal or non-equal force may be utilized without departing from the spirit of the invention.

Our invention is inclusive of means to receive and temporarily support the work W prior to engagement of the mandrels 108 therewith. To this end there is secured to each of the bosses 71 of member 66, a bracket 130 retained in position by screws 131, each bracket supporting an electrically actuated solenoid 132. The bosses 71 also support brackets 134 each secured by means of a screw 135 and a guide pin 136. The screw 135 and pin 136 project into elongated slots in bracket 134 so that the latter may be adjusted in a vertical direction. Pivoted or fulcrumed to the upper portion of each bracket 134 by means of a bolt 137 is a lever 138 having converging upper surfaces 139, 140. The levers 138 are formed to receive removable inserts or fittings 129 which may be of different sizes in order to accommodate different sizes of muffler shells, the inserts being secured by means of screws 133. These inserts engage and support the work W as shown in Figures 4 and 5. An arm of the lever 138 is pivotally connected to a clevis 141 to which is connected the armature 142 of the solenoid 132. The lever 138, in its work supporting position as shown in Figure 4, is maintained therein by the electrical energization of the solenoid by a circuit controlled by cam means hereinafter described. When the solenoid 132 is de-energized, the lever falls to the position indicated in dotted lines in Figure 4 and in full lines in Figure 6. As shown in Figure 4 with 70 the lever 138 in its lowermost position a release of the work W from the mandrels 108 permits the work to drop, engaging lever 138, and as the surface 139 thereof is inclined downwardly, the work will roll to the left as viewed in Figure 4 75

thence on to the inclined ramp 144 formed at the rear portion of the frame 10 to a conveyor or receptacle (not shown).

A portion of the shaft 28 projects outwardly 5 of journal bracket 23 and supports a sleeve 147 held to the shaft by means of a set screw 148, a pair of cams or switch actuating members 149 and 149' being secured to the sleeve by means of screws as shown in Figure 9. The members 10 149 actuate switching means for circuit control hereinafter explained.

Fluid means under pressure are used for actuating the work supporting mandrels and the grooving dies or tools. This means includes the oil or hydraulic pump 16 connected by means of a tube 150 to a pressure relief or unloader valve 151. The unloader valve 151 is connected by means of a pipe 153 to a solenoid actuated valve means 154 for controlling the flow of fluid to and from the groover actuating cylinder 36. A pipe 155 also connects the hydraulic fluid supply from valve 151 through a check valve 156 to a solenoid actuated valve means 157 for controlling the operation of the work supporting mandrels 108. 20 The valve means 157 is connected to the fittings 98 at the outer ends of the cylinders 92 by means of pipe 158, counterbalance valve 160, pipes 159, 161 and 162 to direct fluid into the outer ends of the cylinders. The fittings 99 at the inner ends 25 of cylinders 92 are connected to valve means 157 by means of pipes 165, 166, and 167. The pipes or connections 162 and 167 are made of flexible material to permit adjustment of the mandrel supporting mechanism for accommodation of different lengths of work.

The valve means 154 for controlling the grooving means carried by the sectors 44 is connected to the lower end of the cylinder 36 by means of a pipe 169 and a flexible connection 170. The upper end of cylinder 36 is connected to valve means 154 by pipe 172 and a flexible connection 173. A common return pipe 175 connects the valve means 154 and 157 with the fluid reservoir 17.

The electrical circuits for the arrangement of our invention are illustrated in Figure 11. The motor 15 for driving the fluid pump 16 is connected to a source of electrical energy by means of a main line switch 180, a starting arrangement being illustrated diagrammatically at 181. The service starting and stopping switches for manual control of the motor 15 are indicated at 182 and 183. A switch 184 is provided for initiating the cycle of operations as hereinafter explained. The solenoids 132 and solenoid mechanisms of fluid control valves 154 and 157 are supplied with electrical energy from a current supply line through a master switch 186. A switch 187 is arranged to be actuated by the stops or cams 149 and 149' carried by the sleeve 147 secured on shaft 28. Fluid pressure actuated switches 188 and 189 of the mercoide type are intercalated in the solenoid circuits of the valve means 154 for controlling the reciprocation of piston 38 in cylinder 36.

The operation of the arrangement of our invention is as follows:

The motor 15 is first energized by closing switches 180 and 182, the motor continuing in operation until de-energized by means of switch 183, or 189. The work supporting levers 138 are held in position illustrated in Figure 4 by energization of solenoids 132 upon closing the switch 186, with switch 187 in closed position to complete a circuit through the solenoids. The op-

erator places a cylindrical muffler shell or work W upon the levers 138 as shown in Figure 4 and manually closes the switch 184. This energizes a solenoid in valve means 157 to establish fluid communication under pressure to the outer ends of cylinders 92 from the pump 46 through the medium of pipes 150, 155, 158, 160, 161, flexible tubes 162 and fittings 98. The introduction of oil or other fluid between the pistons 93 and the heads of cylinders 92 moves the pistons 93 inwardly, thus sliding the sleeves 82 toward each other, moving the mandrels 108 into the end portions of the work W. The ends of the work engage the abutment rings 114 and through the springs 126 the work is equalized between the head structures so that the grooves to be impressed in the work will be equidistant from the ends. When the pressure in cylinders 92 attains a predetermined value, viz., a pressure sufficient to actuate mercoid switch 188, the latter is actuated to complete the circuit to one of the solenoids of valve means 154 to establish a pressure fluid connection to the upper end of cylinder 36 above the piston 38 through the medium of pipes 153, 172 and flexible connection 173. As the piston 38 is moved downwardly, it causes clockwise rotation of shaft 28, sectors 44 and grooving dies or tools 53 as viewed in Figure 2, bringing the arcuate projections 55 into rolling engagement with the cylindrical exterior surface of the work and adjacent the annular grooves 110 in mandrels 108. The dies 55 thus roll or impress a pair of grooves into the muffler shell or work W. The muffler shell W is formed with a longitudinal seam 190 where the extremities of the sheet of material forming the cylinder are overlapped or joined, and as illustrated in Figure 4, the seam becomes an abutment, in effect, for the beginning of each groove. The dies 55 do not form grooves or depressions through the seam, but the latter determines the start and completion of the groove, and correspondingly the movement of the sectors 44. The pressure of the dies 55 against the work provides friction for rotating the work and mandrels as the latter are revolvably mounted on anti-friction bearings 100 and 101.

The initial rotation of shaft 28 in bringing the sectors 44 and dies 55 toward the work, rotates the sleeve 147 and, through the medium of the block 149 engaging the switch 187, the latter is moved to a neutral position as shown in Figure 11 to temporarily disconnect the circuit to the solenoids 132, permitting the work supporting levers 138 to move downwardly to the position indicated in dotted lines in Figure 4. Thus the levers 138 do not engage the work during the grooving operation.

When the sectors 44 have rotated an amount completing grooving of the shell W, the block 149 on sleeve 147 engages the switch 187, moving the switch arm in a direction to complete the circuit to a solenoid in the valve means 157 to withdraw the mandrels 108 from the work W. In attaining this result, the fluid under pressure is directed to the inner ends of the cylinders 92 through the medium of pipes 165, pipes 166 and 167, upon the inner sides of pistons 93, and as valve means 157 has disconnected fluid flow to the outer sides of the pistons 93, the latter move outwardly, withdrawing the mandrels 108 from the work W. When the pistons 93 have moved to their extreme outermost positions, fluid pressure builds up in the line and acts upon the mercoid switch 189 to complete the circuit to the solenoid in valve means 154 to disconnect fluid pressure

on the upper side of piston 38 in cylinder 36 and to divert the fluid flow to the opposite side of piston 38 and return the sectors 44 to their initial position.

When the mandrels 108 are withdrawn from the work W, the latter is free to drop downwardly upon the levers 138 (now in position as shown in dotted lines in Figure 4) thence on to the inclined ramp 144 to discharge the grooved work from the machine. As shaft 28 is rotated to its initial position, the block or cam 149 on sleeve 147 engages the arm of switch 187 and closes the circuit to the solenoids 132 whereby the latter are energized to move the levers 138 into position to receive and support a piece of work to be grooved. The cycle of operations as above described is repeated as each piece of work is placed in the machine.

The head 73 is pivotally supported by means of the pins 72 as a safety means in event the dies 55 over-ride a seam 190 of the work. Should this occur, the increased pressure set up on the head 73 causes the springs 74 to be slightly compressed allowing the heads 73 to swing about the axis of pivot pins 72, and in this manner damage to the machine is avoided.

It should be noted that the positions of the heads 73 are rendered longitudinally and transversely adjustable with respect to the frame of the machine, the sectors 44 are adjustable, and the brackets 134 are vertically adjustable so as to render the machine readily adaptable for work of varying lengths and diameters. The dies 55 are removable, and dies of different configuration and lengths may be used, or dies in two or more juxtaposed sections may be employed without departing from the spirit of the invention.

It is apparent that, within the scope of the invention, modifications and different arrangements may be made other than is herein disclosed, and the present disclosure is illustrative merely, the invention comprehending all variations thereof.

What we claim is:

- 45 1. In combination, means for impressing a plurality of grooves in a cylindrical member including a frame; a pair of spaced mandrels mounted on said frame and adapted to support the cylindrical member; a plurality of die carrying sector-shaped elements journaled for oscillation adjacent the cylindrical member; dies mounted upon said elements and adapted for engagement with the exterior surface of the cylindrical member; means to oscillate said elements and dies whereby the latter engage and impress grooves throughout a portion circumferentially of the cylindrical member; and means for automatically withdrawing said mandrels from engagement with the cylindrical member after completion of grooving operations.
- 50 2. In combination, a machine of the character disclosed including a frame; a pair of spaced mandrels mounted on said frame; a pair of levers associated with the frame and adapted to initially receive and support the work; fluid means for moving said mandrels into engagement with the work for supporting the same during the performance of operations upon the work; and automatic means for controlling said levers to render same ineffective to support the work when the mandrels are in work supporting position.
- 55 3. A machine of the character described, in combination, a frame, a pair of housings supported upon said frame; a mandrel rotatably and slidably mounted on each of said housings; fluid
- 60
- 65
- 70
- 75

means for moving said mandrels into engagement with the work; yieldably supported abutments carried by said mandrels for centering the work in the machine; a pair of sectors mounted for oscillatory movement on said frame; a grooving die supported on each of said sectors; fluid actuated means for oscillating said sectors to bring said grooving die into engagement with the work, the friction of engagement with the work serving to rotate the work and supporting mandrels during grooving operations.

4. A machine of the character disclosed, in combination, a frame; a pair of heads adjustably supported on said frame; a mandrel slidably and rotatably supported by each of said heads; a yieldably mounted abutment associated with each of said mandrels adapted to center cylindrically shaped work supported on the mandrels; fluid actuated means for moving said mandrels to work supporting position; electrically energized means for controlling flow of fluid to the fluid actuated means; a shaft; a plurality of sectors adjustable along said shaft; grooving dies mounted on said sectors; and fluid actuated means for moving said sectors to cause the dies to impress peripheral grooves in the cylindrically shaped work.

5. A machine of the character disclosed, in combination, a frame; a pair of levers associated with said frame for receiving and initially supporting cylindrically shaped work; means for operating said levers; a pair of heads supported on said frame; a mandrel slidably and rotatably supported by each of said heads; a yieldably mounted abutment associated with each of said mandrels adapted to center the cylindrically shaped work; means to move said mandrels into engagement with the work carried by said levers; control means for said mandrel actuating means; a shaft; bearings supporting said shaft; a plurality of sectors adjustably supported on said shaft; grooving tools carried by said sectors; means for rotating said shaft to move the tools into engagement with the work to impress peripheral grooves therein, said levers being moved out of work supporting position when said tools are in engagement with the work.

6. A machine of the character disclosed, in combination, a frame; a pair of solenoid controlled levers associated with said frame and adapted for receiving and initially supporting a muffler shell; a pair of heads adjustably supported on said frame, a mandrel slidably and rotatably carried by each of said heads; yieldably mounted abutment associated with each of said mandrels adapted to center the muffler shell in the machine; fluid means for moving said mandrels into engagement with the shell carried by the levers; control means for said mandrel actuating means; a shaft supported on said frame; a pair of sectors adjustable along said shaft and rotatable therewith; grooving tools carried by said sectors; fluid means for rotating said shaft to move the tools into engagement with the muffler shell to impress a pair of peripheral grooves therein; means to move said levers out of work supporting position when the tools engage the shell while the latter is supported by the mandrels; said mandrel moving means being arranged to withdraw the mandrels from engagement with the muffler shell after completion of the grooving operation to discharge the grooved shell from the machine.

7. In combination, a frame; a pair of mandrels mounted on said frame; means for moving said

mandrels longitudinally of said frame to engage a seamed hollow member; a die; a means for oscillating said die for impressing a partial peripheral groove in the unseamed portion of the hollow member; fluid means for actuating said mandrels into and out of engagement with the hollow member; and electrically actuated means for controlling the operation of said fluid means.

8. In combination a frame; a pair of spaced mandrels adapted to support a hollow member upon which the work is to be performed; a die; a sector-shaped element supporting said die; said sector-shaped element being supported whereby said die may be oscillated into rolling engagement with the hollow member to impress a groove therein; a pair of brackets pivoted upon said frame; each of said brackets supporting one of said mandrels; spring means for normally retaining said brackets in position whereby the mandrels support a hollow member during operative engagement of the die with the hollow member, said spring means being adapted to yield upon abnormal contact of said die with the hollow member causing relative movement of said brackets with respect to said frame.

9. In combination, a machine for imparting peripheral configurations in a hollow body including a frame; means for initially supporting the hollow body; a pair of spaced mandrels arranged to be moved into the ends of the hollow body and adapted to support the body during a work performing operation; a sector-shaped element; a die configuration associated with sector-shaped element; means to oscillate said sector-shaped element to move said die into rolling engagement with the hollow body whereby said engagement causes corresponding rotation of said body and impresses the configuration of the die into the body; said means adapted to be withdrawn from engagement with the hollow body after completion of the work performing operation; said initial body supporting means being arranged for movement to an angular position for automatically discharging the body from the machine.

10. A machine of the character disclosed, in combination, a frame; a pair of relatively movable mandrels carried by said frame and adapted to support a tubular member; electrically controlled fluid actuated means for moving said mandrels into and out of engagement with the tubular member; a plurality of sector-shaped arms journaled for oscillatory movement relative to said mandrels; a grooving die associated with each of said arms and adapted for engagement with the tubular member to impress a groove therein throughout a portion circumferentially of the tubular member; and fluid actuated means for oscillating said die into and out of engagement with the tubular member.

11. A machine of the character disclosed, in combination, a frame; a pair of longitudinally movable mandrels carried by said frame and adapted to enter and support the ends of a tubular member; electrically controlled fluid actuated means for moving said mandrels; a pair of sector-shaped arms journaled upon said frame; a grooving die associated with each of said arms; hydraulically actuated means for moving said arms whereby said dies are brought into engagement with the tubular member; electrically actuated means dependent for operation upon the fluid pressure acting on said mandrels when the same are in engagement with the tubular member for directing fluid under pressure to said hydraulic

11

means to move said dies into engagement with the tubular member to impress circumferential grooves therein.

12. In combination, a machine for forming configurations in the walls of hollow members including a frame; a pair of supports movably mounted upon the frame; each of said supports being arranged to telescope into an end of a tubular member; an abutment disposed adjacent each support; yieldable means interposed between each abutment and its respective support; said abutments being arranged to yieldingly engage the ends of the tubular member when said supports are in telescopic engagement with said tubular member; a die; means for actuating the die into engagement with the tubular member and impressing a configuration therein; said yieldable means cooperating with said abutments for properly positioning the tubular member with respect to the die.

13. A machine of the character disclosed, in combination, a frame; a pair of spaced mandrels mounted upon said frame; said mandrels being journaled for rotary movement; said mandrels being arranged for longitudinal movement with respect to the frame to bring said mandrels into telescopic relation with the work; yieldably mounted abutments disposed adjacent said mandrels for centering the work in the machine; a plurality of sector-shaped elements supported upon the frame; grooving tools carried by said sector-shaped elements; and means to oscillate said sector-shaped elements to move said tools into engagement with the work for simultaneously impressing a plurality of grooves in the work.

12

14. A machine of the character disclosed, in combination, a frame; a pair of spaced levers associated with said frame and adapted to receive and initially support the work; a pair of spaced mandrels mounted on said frame; said mandrels being relatively movable into and out of engagement with the work; a pair of grooving dies; sector-shaped elements pivoted upon said frame and arranged to support said grooving dies; means for oscillating said elements to move said dies into engagement with the work when said mandrels are in work engaging and supporting positions, and means rendered effective when said mandrels are in work-supporting position for moving said levers out of engagement with the work whereby the latter is supported solely by the mandrels during grooving operations.

ARTHUR J. BARRIE.
